S. E. NEILL

SWIMMING GLOVE

Filed March 17, 1926

By *Munn & Co.*
Attorney

UNITED STATES PATENT OFFICE.

STRANGE EARL NEILL, OF BAKERSFIELD, CALIFORNIA.

SWIMMING GLOVE.

Application filed March 17, 1928. Serial No. 95,242.

My invention relates to and has for its purpose the provision of an extremely simple and inexpensive device by which swimmers are greatly facilitated to the extent 5 that one may maintain himself afloat with less effort, and greater swimming speed can be attained.

It is also a purpose of my invention to provide a swimming device in the form of 10 a glove adapted to be worn on the hand and having webs between the finger stalls thereof, when the fingers are spread as in swimming, prevent the passage of water between the fingers and thereby cause the 15 hands to act on larger bodies of water in swimming, which as a result greatly facilitates swimming.

I will describe only one form of swimming glove embodying my invention and 20 will then point out the novel features thereof in claim.

In the accompanying drawings,

Figure 1 is a view showing in plan one 25 form of swimming glove embodying my invention with the fingers thereof extended as in swimming;

Figure 2 is a sectional view taken on the line 2—2 of Figure 1;

Figure 3 is a view similar to Figure 1 30 showing the fingers of the glove in normal or non-propelling position;

Figure 4 is a sectional view taken on the line 4—4 of Figure 3.

Referring specifically to the drawings, in 35 which similar reference characters refer to similar parts, my invention, in its present embodiment, comprises a glove formed of any suitable flexible material, such as rubber, the glove including finger stalls 15 and 40 sheets of rubber or other suitable material 16 formed integrally with or secured to the finger stalls in a manner to span the space between the stalls when the latter are in extended position, as shown in Figure 1, and 45 thereby forming webs which function as partitions between the finger stalls to obstruct the passage of water therebetween.

In practice, there are two such devices or 50 gloves which are applied to the hands in the manner of a glove so that the stalls 15 receive the fingers of the hands, it being understood that the shape of the body of each

glove is such as to prevent the accidental removal of the glove from the hand.

In swimming the wearer manipulates his 55 hands in the usual manner and during the propelling stroke of each hand the fingers are spread so as to move the web 16 to the extended position shown in Figure 1. The webs thus form spanning partitions between 60 the fingers, preventing the passage of water between the fingers and thereby causing the hands to act on larger bodies of water, with the result that greater propelling force can be exerted. In the recovering stroke of the 65 hands, the fingers are brought together so that the webs 16 occupy what may be termed as "collapsed" positions, as shown in Figure 3, so that the hand as a whole offers 70 minimum resistance to its return to the starting position of the propelling stroke.

From the foregoing operation, it will be manifest that I have provided a swimming glove which, when applied to the hand of a swimmer, causes the hand to function in 75 swimming in a manner similar to that of the feet of an otter, and whereby with less physical effort a swimmer is capable, by the proper manipulation of his hands, as above described, of maintaining himself afloat and 80 swim with greater speed.

Although I have herein shown and described only one form of swimming glove embodying my invention, it is to be understood that various changes and modifications 85 may be made therein without departing from the spirit of the invention and the spirit and scope of the appended claim.

I claim as my invention:

A swimming device comprising a glove 90 formed of flexible rubber, and sheets of flexible rubber spanning adjacent finger stalls of the glove, said sheets being of substantially triangular contour so that when the stalls are spread apart the sheets provide intervening webs, the sheets having strip portions along the lengths of their edges confronting adjacent stalls, forming continuations of and projecting laterally to one side only of the sheets, the said portions 95 providing attaching surfaces by means of which the sheets are secured to the stalls.

STRANGE EARL NEILL.
